UNITED STATES PATENT OFFICE

WILLIAM C. FORK AND WILLIAM C. KRONQUEST, OF CHICAGO, ILLINOIS, ASSIGNEES
TO ACME STEEL COMPANY, OF CHICAGO, ILLINOIS, A CORPORATION OF ILLINOIS

RIM FOR TUBS

Application filed January 9, 1925. Serial No. 1,351.

This invention relates to an improved process of forming rims adapted for use on the covers of butter tubs and the like and to an improved construction of such a rim. The improved process of forming rims herein described is claimed in applicants' pending divisional application Serial No. 137,720, filed September 25, 1926. As heretofore constructed, butter tubs have been made of wooden staves secured in position by means of hoops and the covers of the tubs have been provided with wooden rims adapted to extend downwardly over the walls of the tubs. These wooden rims are cylindrical in form and have a considerable vertical height so that they must necessarily be packed end to end when being shipped from the manufacturer to the user of the tub and they therefore occupy a large amount of space. It is the principal object of the present invention to provide an improved metallic rim adapted particularly for use on the covers of butter tubs. A further important object is to provide an improved process by which the improved rim may be conveniently and cheaply formed from sheet metal. Still another important object of the invention is to provide a rim of such formation that a large number of rims may be nested one within the other to form a compact package. A further object is to provide a process of forming the rim whereby the body of the rim is given a flared formation while, at the same time, great strength is imparted to the rim so that it may be conveniently packed and efficiently used. Other objects relate to various features of the process and of the construction of the rim such as will appear more fully hereinafter.

The nature of the invention will be understood from the following specification taken with the accompanying drawings in which one method of forming the rim and one form of the construction thereof are disclosed.

In the drawings, Figure 1 shows a somewhat diagrammatic side elevation of a form of apparatus which may be employed in the process of forming the improved rim; Fig. 2 shows an enlarged side elevation of a portion of the sheet metal band which is formed

by the first step of the process; Fig. 3 is an enlarged vertical section taken on the line 3—3 of Fig. 1 showing the formation of the peripheral surfaces of the rolls which operate on the sheet metal band after it has been formed as illustrated in Fig. 2; Fig. 4 shows an enlarged sectional view taken on the line 4—4 of Fig. 1, illustrating the means for corrugating the flange which is formed on the band by the rolls illustrated in Fig. 3; Fig. 5 is a sectional view taken on the line 5—5 of Fig. 1 showing the portions of the rolls by which the body portion of the sheet metal band is corrugated and given a flared formation; Fig. 6 is an enlarged perspective view of a portion of the completed rim; Fig. 7 is a perspective view of the complete rim in its finished form; Fig. 8 is an enlarged vertical section taken through the axis of a butter tub illustrating the application of the improved rim thereto; Fig. 9 is a side elevation of a package of butter tub rims showing the nested relation thereof, a part of the package being shown in vertical section; and Fig. 10 shows a perspective view of a butter tub having the improved rim of the present invention applied to the cover thereof.

In practicing the invention, it is desirable to form the rim from a band of sheet metal which is relatively thin in order that the completed rim may be manufactured at a relatively low cost to enable it to compete with the wooden rims heretofore used. Various forms of apparatus may be employed in practicing the improved process, but, by way of illustration, there is shown in Fig. 1 a diagrammatic view of a series of rolls and cooperating apparatus which may be a modification of the form of hoop making apparatus disclosed in U. S. Patent No. 1,508,570, dated September 16, 1924. In the operation of this apparatus, a band 15 of sheet metal of suitable width and thinness is fed from a roll by means of suitable power driven feeding rollers, not shown, onto a table or guideway 16. The sheet metal band 15 is intermittently brought to rest on the guideway 16 and it is then operated on by a pair of downwardly moving plungers 17 and 18, the plunger 17

carrying a knife 19 and a punch 20, while the plunger 18 carries a punch 21 and a knife 22. The knife 19 cooperates with a cutting edge 23 on the guideway 16 to sever the band 15 along the line 24, as shown in Fig. 2, thus severing a strip 25 of sheet metal which is of suitable length for forming the butter tub rim. The knife 19 is of such form that the severed edge 24 is curved adjacent one side of the strip 25 as shown at 24^a, thus leaving at the end of the body portion of the band 15 a sharp projection 26. This projection is cut from the end of the strip 25 by the knife 22 cooperating with the cutting edge 27 on the guideway 16. At the same time that the strip 25 is severed from the band 15 and the projection 26 is cut from the end of the strip, to form a rounded surface 26^a, the punches 20 and 21 operate to form in the strip 25 two holes 29 located adjacent the ends of the strip for engagement by nails or tacks when the rim is applied to the cover of the butter tub. After the strip 25 has been formed, it is fed longitudinally of the table 16 by rollers 30, this feeding operation occurring after the plungers 17 and 18 have been elevated, and the strip 25 is thereby caused to pass between two rolls 31 which are mounted on horizontal axes and arranged to coact with the strip 25 to impart to it the form illustrated in Fig. 3, where the band 15 is shown as having a half-bead 32 of substantially semi-circular cross section at one edge thereof, while the other edge is bent transversely to form a flange 34. The half-bead 32 is formed by a projection 35 on one of the rolls 31 engaging the sheet metal of the band and forcing it into a depression 36 of similar formation formed in the other roll 31. The flange 34 is formed by the shoulder 37 on one of the rolls 31 overlapping the periphery of the other roll 31. After passing the rolls 31, the strip of sheet metal, having the cross section illustrated in Fig. 3, is operated on by a pair of corrugated rolls 38, mounted to revolve on vertical axes and arranged to operate only on the flange 34 of the strip so that this strip is corrugated, as indicated in Fig. 4, during the passage of the strip between these rolls, the axes of these corrugations 39 extending transversely to the edge of the flange. The thinness of the sheet metal permits it to stretch sufficiently during the process of corrugation of the flange 34 without buckling or warping the body portion 40 of the strip of sheet metal between the flange 34 and the half-bead 32, this body portion having a width considerably greater than that of the flange 34.

After the flange 34 has been corrugated, the strip 25 is engaged by a pair of rolls 41 which are mounted to revolve on horizontal axes and which are provided on their peripheral surfaces with corrugations 42. The corrugations may be tapered transversely of the

rolls or the axes of the rolls 41 may be relatively inclined to a slight extent so that the rolls 41 produce in the body portion 40 of the strip 25 a continuous series of corrugations 43 which decrease in depth from the corrugated flange 34 toward the half-bead 32, preferably disappearing entirely before the half-bead 32 is reached, as illustrated in Fig. 6. In the process of forming the tapered corrugations 43, the strip of sheet metal is contracted along and toward the edge on which the corrugated flange 34 is formed so that the body portion of the sheet metal rim between the bead 32 and the flange 34 is flared outwardly from the corrugated flange, as illustrated in Fig. 7. The previous formation and corrugation of the flange 34 makes it possible to form the tapered corrugations 43 without stretching the metal and without buckling the flange 34 because the corrugations in the flange 34 lend themselves to the contraction of that edge of the rim on which this flange is formed. The corrugating rolls 41 force the metal strip 25 upwardly over the concave face of a die block 44 thus imparting to the strip the circular curvature of the completed rim 45, having the form shown in Fig. 7. The provision of corrugations in the flange 34 and in the body portion of the rim results in imparting great strength to the finished rim and also in giving it a flared formation which permits the nesting of the completed rims one within the other after they have been applied to the covers.

As shown in Figs. 8, 9 and 10, the rim 45 is applied to the wooden butter tub cover 46 with the corrugated flange 34 overlying the upper surface of the cover and with the flared body portion 40 seated against the correspondingly flared edge surface 46^a of the cover. The rim is secured to the cover by small nails or staples 47 which are driven through the body portion 40 of the rim into the edge of the cover, as shown in Fig. 10. The overlapping ends of the rim are united by a nail or staple 48 driven through the holes 29 into the cover, or the holes 29 may be formed by the driving of the nail or staple, a method which eliminates the difficulty of securing an alignment of previously formed holes when the ends of the rim are overlapped.

The nested arrangement of the completed rims is illustrated in Fig. 9 where a series of rims 45 are shown applied to the covers 46 and mounted one within the other with the flanges 34 extending inwardly and the half-beads 32 located one above the other on the outer side of the package. In securing the covers together in the nested package, wooden blocks 49 may be mounted within the rims, resting on the upper cover 46, and sheet metal straps 50 may be passed around the package and secured to the blocks 49 by nails 51.

The user of the covers applies them to the

butter tubs in the manner illustrated in the Figures 8 and 10. The tub 53 is shown as comprising a plurality of staves 54 which are surrounded by a plurality of sheet metal hoops 55 each of which is formed with a complete cylindrical bead 56 along its lower edge so that when the hoops are driven onto the tub from the bottom thereof, the edge of each hoop opposite the bead thereon is adapted to stretch sufficiently to permit the hoop to take on a tapered or flared formation corresponding to that of the external surface of the tub. When the cover is placed on the tub the rim 45 projects downwardly over the upper edge of the tub, thus preventing access of moisture and dust to the interior of the tub through the crack between the cover and the upper ends of the staves 54.

It will be apparent that by means of the foregoing process, an improved sheet metal rim has been provided which may be manufactured at a sufficiently low cost and which possesses sufficient strength to compete successfully with other types of rims heretofore used. Not only does the improved rim possess increased strength and stiffness but it has a desirable flared formation which permits large numbers of them to be nested in a compact package for shipment.

Although one form of the improved rim and one method of forming it have been shown and described by way of illustration, it will be understood that the rim may have various forms and be formed in various ways within the scope of the appended claims.

We claim:

1. The combination with a tub cover of a rim having an outwardly and downwardly flared body portion extending below the lower edge of said cover and having a flat annular inwardly extending flange contacting with said cover from said body portion inwardly, said body portion being adapted to extend downwardly around the upper portion of a tub on which said cover is seated.

2. The combination with a tub cover having a peripheral edge surface in the form of a truncated cone having an annular surface flaring downwardly and outwardly, of a rim seated on said surface and secured to said cover and having its body portion outwardly flared and transversely corrugated.

3. The combination with a tub cover having a peripheral edge surface in the form of a truncated cone, of a rim seated on said surface and secured to said cover and having its body portion outwardly flared and transversely corrugated, said corrugations being tapered transversely of the rim.

4. The combination with a tub cover having a peripheral edge surface, of a rim comprising a circular sheet metal strip seated on and secured to said surface and provided with corrugations having their axes extending

transversely of said strip, said corrugations being tapered longitudinally of their axes.

5. The combination with a tub cover having a peripheral edge surface in the form of a truncated cone, of a rim comprising a circular sheet-metal strip seated on and secured to said surface and provided with corrugations having their axes extending transversely of said strip, said corrugations being tapered longitudinally of their axes.

6. A rim for tub covers comprising a body portion having an annular bead along one edge and an annular flange along the other edge, the part of said rim between said flange and said bead being flared and corrugated.

7. A rim for tub covers comprising a body portion having an annular bead along one edge and an annular flange along the other edge, said body portion being corrugated between said bead and said flange, said corrugations having their axes extending transversely of said body portion and being tapered longitudinally of their axes to impart a flare to said rim.

8. The combination with a tub cover having a peripheral edge surface in the form of an upright truncated cone, of a rim comprising a circular sheet-metal strip flared downwardly and outwardly to seat on said edge surface of said cover, and means for securing said rim on said cover.

9. The combination with a tub cover having a peripheral edge surface, of a rim secured to said cover and extending downwardly around and beyond said edge surface, said rim being provided with corrugations having their axes extending transversely of said rim, and a flange formed on said rim and seating on the upper surface of said cover, said flange being provided with corrugations tapered transversely thereof.

10. The combination with a tub cover having a peripheral edge surface, of a rim secured to said cover and extending downwardly around and below said edge surface, said rim being provided with corrugations having their axes extending transversely of said rim and being tapered longitudinally to cause said rim to flare downwardly and outwardly, said rim being further provided with a bead around the lower edge thereof, and a flange formed on the upper edge of said rim and seating on the upper surface of said cover, said flange being provided with tapered corrugations extending transversely thereof.
